UNITED STATES PATENT OFFICE

2,666,280

ABRADING THE INTERIOR SURFACES OF
HOLLOW WARE

Richard G. Riedesel, Stillwater, Theodore J. Miller, St. Paul, and Lawrence A. Martin, White Bear Township, Ramsey County, Minn., assignors to Minnesota Mining & Manufacturing Company, St. Paul, Minn., a corporation of Delaware

Original application May 31, 1947, Serial No. 751,590, new Patent No. 2,573,220, dated October 30, 1951. Divided and this application July 26, 1951, Serial No. 238,662

5 Claims. (Cl. 51—142)

1

This invention relates to abrading, grinding and/or polishing the interior surfaces of hollow ware such, for example, as aluminum cookers, pans, kettles, etc., also vats, tanks and the like.

Methods previously used have been principally hand operations; and the few machines that have been tried have been crude and inadequate, necessitating much hand labor. All of the said methods and machines heretofore known have had numerous defects, including particularly the inability to produce true surfaces. The provision of means and methods for the production of such interior surfaces is accordingly one of the objectives of this invention.

The invention provides a double roll grinder wherein a piece of hollow ware is rotated about its axis and a rotating abrasive wheel is thrust into the cavity into contact with the interior surface. The work and the wheel are then moved in relation to each other in a manner to cause the wheel to advance along a path complementary to the said surface. A second rotating wheel, in addition to the first, is thrust into the cavity into contact with the surface. The second wheel may be held against the surface without movement other than its own rotation and the rotation of the surface.

The abrasive wheels are in the form of pulleys or rolls carrying on their peripheries endless abrasive belts.

An illustrative embodiment is hereinafter described and diagrammatically illustrated in the accompanying drawings in which:

Figures 1 and 2 are plan and side elevational views, respectively, of an abrasive belt machine for abrading the interior surfaces of hollow ware;

Figure 3 is a front elevation of a pan and the contact wheels or rolls; and

Figure 4 is a perspective view of a pan.

A chuck 46 adapted to hold the workpiece that is to be abraded, such as the pan 47, is fixed on the shaft 48 of a motor 49. The motor is on a table 50 which is slidably mounted in ways 51 in a rack 52. This construction, together with the feed screw assembly 54, provides means for reciprocal axial movement of the chuck, that is, reciprocal movement in the direction of the chuck's axis, as indicated by the arrows.

An abrasive belt assembly, comprising rotatably mounted pulleys 56, 57 and 58 which carry an endless abrasive belt 59, is positioned in front of the chuck 46 with the pulley 56 adjacent the face of the chuck so as to extend into the interior of the pan 47 when the latter is held in the

2

chuck. The pulley 56 has a resilient periphery and serves as a contact wheel or roll for pressing the belt 59 into contact with the work. The belt passes around the wheel's periphery so that the wheel 56 is, in effect, an "abrasive surfaced wheel."

The wheel 56 is rotatably mounted on the end of an arm or lever 60 which pivots around a shaft 61 in a plane determined by the chuck's axis. 10 Downward movement of the lever, as indicated by the arrow in Figure 2, which is limited by the stop 62, raises the wheel 56 to bear upwardly against the inner surface of the side of the pan 47. The belt 59 is driven by the pulley 58 which is rotated by a motor 63.

Below the belt 59 is a second abrasive belt assembly comprising rotatably mounted pulleys 66, 67 and 68 which carry an endless abrasive belt 69, positioned with the pulley or roll 66 adjacent the face of the chuck 46 so as to extend into the interior of the pan 47 when the latter is held in the chuck. The roll or pulley 66 has a resilient periphery and serves as a contact wheel or roll for pressing the belt 69 into contact with the work, and is, in effect, an "abrasive surfaced wheel." The roll 66 is rotatably mounted on an adjustable arm 70. The arm is pivotally supported to permit positional adjustment (up and down) of the roll 66, a nut 71 being provided to lock the arm in desired position. The belt 69 is driven by the pulley 68 which is rotated by the motor 63.

In operation, the pan 47 is centered in the chuck 46 and fixed therein with its concave surface that is to be abraded, facing outwardly. 35 The stop 62 is then adjusted so that when the lever 60 bears down against it, the periphery of the contact roll 56 will contact the inside edge of the pan, as indicated in Figure 3. The nut 71 is loosened, the arm 70 is raised or lowered until the center of the roll 66 is on a level with the center of the pan, and the nut 71 is then tightened.

The motor 63 is started, driving the abrasive belts 59 and 69 in the direction of the arrows in Figure 2; the motor 49 is started, rotating the pan 47 clockwise as shown in Figures 3 and 4; and the crank 54 is then turned to advance the chuck assembly toward the belt assemblies.

50 When the edge of the spinning pan comes within reach of the wheel 56, the lever 60 is held (manually) downwardly against the stop 62, and a downward pressure is maintained while the chuck advances, thereby continuously pressing the wheel 56 upwardly against the inside side of

the pan. The said manual pressure, however, should be yieldable, so that as the chuck advances, the wheel 56 may move downwardly in response to the pressure of the converging sides of the pan and follow their contour. The net effect is to rotate the arm 60 about its pivot 61 and thereby to move the wheel downwardly (which is "transversely" in respect to the chuck and the pan) in a plane determined by the chuck's axis.

When the chuck has advanced until the wheel 56 extends into the pan so as to contact the bottom of the pan, as shown in Figure 2, the turning of the crank 54 is stopped. Movement of the bottom of the pan into contact with the wheel 56 will also have moved the bottom into contact with the wide contact roll 66, and the entire inside surface of the pan will then have been abraded, the curved side area by the wheel 56, the planar bottom area by the roll 66.

Referring to Figure 4, the geometrical axis of the pan 47 is represented by the dotted line *ab*, which is at the same time the axis of rotation of the pan and of the chuck 46. The dotted line *cd* is complementary to an axial section of the inside surface of the pan and lies in a plane that is determined by the said axis. The solid line 73 is complementary to an axial section of the inside surface of the pan and lies in a plane that is determined by the said axis.

In the above described operation of the machine, the path of the point of contact of the wheel 56 is the line *cd*, although in practice it is frequently desirable for the line to be slightly to the right or left of *cd*. This is true particularly where, as in the described machine, the abrasion is by a belt carried by the periphery of the contact wheel as contrasted with abrading by a solid abrasive wheel. In the described machine, if the pan rotates clockwise, the preferred path of the point of abrading contact is along a line slightly to the right of the line *cd*, as indicated by the solid line 74. The two lines, however, are in practice interchangeable and are so very close together that, for the purposes of this invention as defined in the claims, they are regarded as equivalents and are both embraced in the phrase "a path complementary to an axial section of the surface" and in the phrase "in a plane that is determined by the axis of rotation of the surface," as those phrases are used herein.

The line of contact of the wheel or roll 66 is the line 73. This too may vary slightly above or below its described position, but since there is little or no lateral pressure on this roll, such variance renders little, if any, advantage.

There are numerous other variables, all of which are contemplated as coming within the scope of the claimed invention. For example, the size and shape of the contact rolls 56 and 66 may vary widely, such variance being governed largely by the size and shape of the concave surfaces being abraded. The width of the belts may vary accordingly. The length of the belts may also vary. For example, one model of the machine accommodates an upper belt (59) averaging 110 inches in length, and a lower belt (69) of somewhat longer length.

The periphery of the contact roll or wheel 56 is preferably curved in cross section sufficiently to clear, or at least to complement, the circular side of the pan being abraded, as shown in Figure 3; and the wheel itself is preferably of a sufficiently small radius to enable it to clear, or

at the most to complement, the curve between the side and bottom of the pan, as shown in Figure 2.

The lower contact roll 66, being stationary, its periphery must be shaped to conform to or complement the surface which it abrades. Such surface being here illustrated as substantially flat or planar, the roll 66 is consequently cylindrical with substantially straight sides. If the bottom of the pan were curved, the sides of the cylinder (the periphery of the roll) would be curved accordingly. The width of the roll is preferably sufficient to support a belt whose width extends from the edge of the area that is abraded by the upper roll 56 to the center of the pan, preferably to a point slightly past the center; in fact, if desired, it may extend clear across the pan to the opposite edge so as to have approximately twice the width of the illustrated roll 66.

Although the roll or wheel 56 is referred to herein as the "first" wheel and 66 as the "second," and 56 is described and illustrated as the first to contact the work, the construction may be altered so that 66 is the first to make contact, if desired. Insertion of the roll 66 may be before, during or after the operation of 56.

Transverse movement of the wheel 56 in relation to the chuck or pan, in a plane determined by the chuck's axis is here shown as being accomplished by movement of the wheel, the wheel being raised and lowered by the lever 60. It may also be accomplished by moving the chuck, e. g., the arm 60 may be fixed and the chuck assembly mounted in ways for reciprocal vertical movement; or it may be accomplished by movement of both the wheel and the chuck.

The axis of the wheel 56 is shown as lying in a plane perpendicular to the plane of its own transverse movement. If desired, the construction may be altered so that the axis of the wheel will lie in the plane of its own transverse movement.

The peripheries of the contact rolls may vary from hard and unyielding metal or wood or other material to very soft and/or highly resilient rubber or other material, depending on the material being abraded, the speed of cut and the quality or type of finish that is desired.

The chuck and belt speeds may vary over a wide range. For example, ranges frequently employed in the illustrated machines are 600 to 2000 revolutions per minute for the chucks and 2000 to 3500 surface feet per minute for the belts. The chuck and belt speeds in their relation to each other may also vary. Generally, a belt speed that is slow in relation to the speed of the chuck or surface being ground, produces a slow cut and a smooth finish. A higher relative belt speed increases the cut but gives a rougher finish. A surface being abraded can be rotated so as to move with or against the movement of the belt. By the almost infinite number of possible combinations of relative speeds and directions of movement between the surface being abraded and the abrasive elements, a corresponding variety of kinds of finish may be obtained.

The sizes and shapes of vessels whose interior surfaces may be abraded by machines that embody this invention may vary widely.

Although the illustrated machines are designed for manual operation of the feed mechanisms they could be equipped with mechanical feeds to make the machines partially or entirely auto-

matic without departing from the claimed invention.

This is a division of our copending application Serial No. 751,590 filed May 31, 1947, which later issued to Richard G. Riedesel and Lawrence A. Martin as Patent No. 2,573,220 on October 30, 1951, with claims to a single roll grinder.

What we claim is:

1. In a machine for abrading the interior surfaces of hollow ware, a work holding chuck, means for rotating the chuck, means for effecting reciprocal axial movement of the chuck; a first abrasive belt assembly comprising rotatably mounted pulleys for supporting an endless abrasive belt, one of the pulleys being positioned adjacent the face of the chuck to serve as a contact wheel to apply the belt to the slide surface of the work, means for mounting the contact wheel for movement in a plane determined by the chuck's axis, and means for rotating one of the pulleys to drive the belt; and a second abrasive belt assembly comprising rotatably mounted pulleys for supporting an endless abrasive belt, one of the pulleys being positioned adjacent the face of the chuck to serve as a contact roll to apply the belt to the bottom surface of the work, and means for rotating one of the pulleys to drive the belt.

2. The device of claim 1 in which the axis of the contact wheel in the said first assembly is in a plane perpendicular to the said plane in which the contact wheel of the first assembly moves.

3. In a machine for abrading concave surfaces, a work holding chuck, means for rotating the chuck, means for effecting reciprocal axial movement of the chuck; a first abrasive belt assembly comprising an arm, a pulley rotatably mounted

5 at one end of the arm, means for mounting the arm in front of the chuck with the pulley adjacent the face of the chuck to serve as a contact wheel to apply the belt to the side surface of the work, the said mounting means including a pivotal mounting for effecting rotation of the arm, at least one other pulley rotatably mounted in alignment with the contact wheel pulley, and means for rotating one of the pulleys to drive the belt; and a second abrasive belt assembly comprising rotatably mounted pulleys for supporting an endless abrasive belt, one of the pulleys being positioned adjacent the face of the chuck to serve as a contact roll to apply the belt to the bottom surface of the work, and means for rotating one of the pulleys to drive the belt.

10 4. The device of claim 3 in which the rotation of the first arm is in a plane determined by the chuck's axis.

20 5. The device of claim 4 in which the axis of the contact wheel in the said first assembly is in a plane perpendicular to the said plane in which the first arm rotates.
